UNITED STATES PATENT OFFICE.

MAHLON F. SMITH, OF MONTICELLO, INDIANA.

FARM-GATE.

SPECIFICATION forming part of Letters Patent No. 430,702, dated June 24, 1890.

Application filed February 7, 1890. Serial No. 339,619. (No model.)

To all whom it may concern:

Be it known that I, MAHLON F. SMITH, a citizen of the United States, residing at Monticello, in the county of White and State of Indiana, have invented certain new and useful Improvements in a Farm-Gate, of which the following is a full, clear, and exact description, that will enable others to make and use the same, reference being had to the accompanying drawings, forming a part of this specification.

This invention relates to an improved farm-gate; and the same consists of certain novel features in the construction, combination, and arrangement of the several parts, whereby a strong, light, and durable structure is provided at a low cost.

Figure 1 is a side elevation of a gate embodying my improved features, and Fig. 2 a view in perspective of one of the hinge parts attached to the gate.

Referring to the drawings, A A represent the two uprights forming the respective ends of the gate, and B a horizontal connecting-bar, having its ends mortised in said uprights at their longitudinal centers. Thus the wooden part of the structure consists of the said three parts.

The horizontal tie-rods a a are formed of twisted wire and connect the uprights above the bar B. The companion tie-rods a' a' a' are arranged below the wood connecting-bar in the same manner, and all are provided with loops a² to permit the same to be conveniently twisted taut to maintain the required strain.

The diagonal tie-rods or struts b b give additional strength to the structure.

The respective angle hinge members C are rigidly secured to the outer sides of the upright members of the gate-frame, the horizontal part of these hinges being provided on each side with notches b'. The truss-rods D are also composed of twisted wires and are located outside of the respective ends of the gate, as shown. The vertical part of the truss-rods lies between the hinge members, the untwisted part engaging with the notches b' in the respective sides of the horizontal part of the hinge members, and the terminal loop ends d of said trusses passing around the upper and lower ends of the respective uprights of the gate-frame. The loops d' in the trusses permit of the same being strained taut. By means of these trusses, together with the horizontal and diagonal tie-rods, the gate-structure may be made always to retain its shape and the parts prevented from sagging.

Having thus described my invention, what I claim as new, and desire to secure by Letters Patent, is—

A farm-gate consisting of the two uprights forming the ends, the horizontal bar connecting said uprights, the horizontal tie-rods, the diagonal tie-rods, the truss-rods, and the notched hinge members, constructed and arranged substantially as described.

MAHLON F. SMITH.
